Primary Examiner — Kevin K Rudzinski(74) *Attorney, Agent, or Firm* — Mitchell Law PLLC; Matthew W. Mitchell**CLAIM**

The ornamental design for a wearable dog walking apron, as shown and described.

DESCRIPTION

FIG. 1 is a front isometric view of the wearable dog walking apron of the present invention;

FIG. 2 is rear isometric view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown around the perimeter of the pockets represent stitching and form part of the claimed design. The broken lines showing mechanical fasteners on the strap, the carabiner, the D-shaped links, and the graphic indicia, illustrate portions of the wearable dog walking apron that are not claimed. The cross hatching shown indicates a fabric material only and does not represent any particular color, texture, pattern, or finish of fabric, except for the cross-hatched pocket on the front right pocket with respect to FIG. 3, there the hatching represents a mesh fabric.
